FIG. 5 is a bottom view thereof;

FIG. 6 is a top view thereof;

FIG. 7 is a rear view thereof;

FIG. 8 is a perspective view of an RFID/NFC tag mount according to a second embodiment of the design;

FIG. 9 is a left side view according to a second embodiment thereof;

FIG. 10 is a front view according to a second embodiment thereof;

FIG. 11 is a right side view according to a second embodiment thereof;

FIG. 12 is a bottom view according to a second embodiment thereof;

FIG. 13 is a top view according to a second embodiment thereof;

FIG. 14 is a rear view according to a second embodiment thereof;

FIG. 15 is a perspective view of an RFID/NFC tag mount according to a third embodiment of the design;

FIG. 16 is a left side view according to a third embodiment thereof;

FIG. 17 is a front view according to a third embodiment thereof;

FIG. 18 is a right side view according to a third embodiment thereof;

FIG. 19 is a bottom view according to a third embodiment thereof;

FIG. 20 is a top view according to a third embodiment thereof;

FIG. 21 is a rear view according to a third embodiment thereof;

(Continued)

FIG. 22 is a perspective view of an RFID/NFC tag mount according to a fourth embodiment of the design; FIG. 23 is a left side view according to a fourth embodiment thereof; FIG. 24 is a front view according to a fourth embodiment thereof; FIG. 25 is a right side view according to a fourth embodiment thereof; FIG. 26 is a bottom view according to a fourth embodiment thereof; FIG. 27 is a top view according to a fourth embodiment thereof; and, FIG. 28 is a rear view according to a fourth embodiment thereof.
